Application April 2, 1943, Serial No. 481,648

4 Claims. (Cl. 102—81)

1

This invention relates to fuses and more particularly to a novel hydrostatically armed fuze for underwater explosive devices, which comprises safety means for maintaining the fuze unarmed, and a device normally locking the safety means in its safe position and operable hydrostatically to release the safety means and permit firing of the fuze. The new fuze may be made in a simple and compact form and is positive in operation and safe to handle.

One object of the invention resides in the provision of a novel hydrostatically armed fuze which is simple and compact in construction by reason of its inclusion of a bell-crank lever forming part of the arming device. A fuze made in accordance with the invention comprises a bell-crank lever having one arm normally locking a safety means in its safe position to prevent firing of the fuze, the other arm lying adjacent a diaphragm, or the like, operable by fluid pressure to move the lever and release the safety means so as to permit firing of the fuze. In the preferred construction, the safety means are normally held in the safe position by a pair of opposed bell-crank levers having corresponding arms interlocked with the central portion of the diaphragm to prevent movement of the levers independently of the diaphragm. With this construction, the lever connection between the diaphragm and the safety means may be made in a symmetrical form occupying a relatively small space, and because of the symmetry of the levers, sidewise blows on the fuze tending to move one of the levers away from the safety means also tend to move the other lever toward the safety means so as to insure against movement of the latter from its safe position.

Another object of the invention is to provide a fuze of the character described having a firing pin and dual safety means including a gate normally rendering the firing pin ineffective and a striker head normally securing the pin against operation, both of which are held positively in their safe positions by the hydrostatic device and are released by operation of the device. Preferably, the gate and head are locked in their safe positions by opposed arms of the bell-crank levers, the free end portion of each arm locking one of the safety means and the intermediate portion of each arm locking the other safety means.

A further object of the invention resides in the provision of a novel fuze having a firing pin and a striker head for securing the pin against operation and movable by either head-on or side-wise impact of the fuze to release the firing pin.

2

Another object of the invention is to provide a hydrostatically armed fuze including novel means for preventing accidental operation of the hydrostatic device.

5 These and other objects of the invention may be better understood by reference to the accompanying drawings, in which

Fig. 1 is a longitudinal sectional view of one form of the new fuze;

10 Fig. 2 is a sectional view on the line 2—2 in Fig. 1;

Fig. 3 is a longitudinal sectional view of a modified form of the fuze;

15 Fig. 4 is a similar view of still another form of the fuze, and

Fig. 5 is a side view partly in section showing a modification of the fuze illustrated in Fig. 4.

Referring to the drawings, I have shown for 20 illustrative purposes an embodiment of my invention for use in antisubmarine explosive projectiles. The fuze is adapted to be mounted in the nose portion of the projectile and to detonate the high explosive charge in the projectile casing on impact with a submerged submarine.

25 The fuze, as shown, comprises a cylindrical casing 10 containing a hollow cylindrical body 11 which is mounted in spaced, concentric relation to the casing wall on a flange 11a integral with the body at its rear end. The flange 11a fits closely in the casing and is supported on its front face by a set of sleeves 12 disposed lengthwise in the casing and secured by posts 13 extending through the sleeves. At their rear ends, the posts project through the sleeves and are threaded in the flange, while the front ends of the posts are threaded in the nose portion of the fuze to be described presently. The body 11 is formed with a longitudinal bore for receiving a firing pin having a point 14 at its rear end and a shank 14a extending forwardly from the point through the bore.

30 An operating spring 15 is coiled around the shank and is compressed between a flange 16 on the pin and a shoulder in the bore. At its front end, the body 11 is formed with hollow concentric bosses 17 and 18, the inner boss 18 having openings for receiving a set of ball bearings 19. The bearings are disposed partly in the boss 18 where they contact a bevelled surface on a cam 20 which is connected to a reduced portion of the firing pin 40 at its front end, the reduced portion partly defining an annular recess 21 adjacent the bearings. The ball bearings 19 are normally held against the cam 20 by a striker head 22 having a rearwardly extending hollow boss formed with an internal annular recess 23 for receiving the bear-

50

ings. The striker boss terminates between the bosses 17 and 18 on the body 11 and has an external shoulder 24 abutting against the front end of the outer boss 17. It will be observed that the bearings 19 support the striker head and are held by the head on the cam 20 to lock the firing pin in a retracted position against the spring 15.

In its rear face, the body 11 has a transverse channel 26 containing a safety gate 27, the gate having an opening 28 for receiving a semi-cap (not shown). The gate is slideable in the channel 26 and is normally locked, by means to be described presently, at one end of the channel in a safe position (Fig. 2) so as to offset the opening 28 a substantial distance from the firing pin 14, whereby firing the semi-cap due to accidental operation of the firing pin is prevented. Movement of the gate to its armed position is effected by compression springs 29 seated in longitudinal bores in the gate and having caps 30 on their outer ends engaging the inner wall of the casing.

The firing pin assembly including flange 11a is held in the casing by a retaining ring 31 threaded in the rear end of the casing. A disc 32 is mounted in the central opening of the retaining ring on the rear face of the flange 11a and the gate 27 and has a central opening 33 aligned with the firing pin. The disc 32 is clamped against the flange 11a by a booster cap 34 threaded in the retaining ring and containing the usual booster charge, such as tetryl (not shown), for detonating the main charge in the projectile.

Intermediate its ends, the gate 27 is formed with slots 36 in its side walls for receiving the free ends of the arms 37 and 37a of a pair of opposed bell-crank levers for locking the gate. The levers are mounted on opposite sides of the body 11 and are movable outwardly in radial slots 38 in the flange 11a. The lever arms 37 and 37a are provided intermediate their ends with shoulders 39 and 39a, respectively, disposed directly in front of the striker flange 24 and closely adjacent thereto. It will be apparent that when the lever arms 37 and 37a are in their innermost positions, the shoulders 39 and 39a prevent movement of the striker head 22 due to impact of the fuze, while the rear ends of the lever arms engage in the gate slots 36 so as to lock the gate positively in its safe position against the action of springs 29.

In the front end of the casing 10 is a split nose disc 40 made up of two sections which are separated to form a transverse slot 41 for receiving the bases of the bell crank levers 37 and 37a. The levers are pivotally mounted on pins 42 extending across the slot 41 and held at their ends in the opposed sections of the disc 40, the pins having suitable shoulders for holding the disc sections in expanded positions against the inner wall of the casing. The rear face of the nose disc 40 engages the adjacent ends of the sleeves 12, and the front ends of the posts 13 are threaded into the nose disc.

A pre-stressed diaphragm 44 is seated on the front end of the casing and is clamped in position around its periphery by a nose cap 45 threaded on the outside of the casing. The inner face of the nose cap is recessed to form a chamber 43 adjacent the diaphragm, and the chamber communicates through a central recess 47 in the cap with radial passages 48 extending through the side wall of the cap. The diaphragm is normally dished outwardly, as shown, but when it is subjected on its outer face to a fluid pressure

of a predetermined magnitude, its pre-stressing is overcome and it snaps abruptly to a position of opposite curvature into a recess in the front face of the nose disc 40.

On the central portion of the diaphragm is a button 50 having a head which overlies the free ends of the other arms 51 and 51a of the bell crank levers. The arms 51 and 51a extend inwardly adjacent the diaphragm and are confined at their free ends between the diaphragm and the head of the button 50, whereby the arms are interlocked with the diaphragm. The button projects through the diaphragm and is connected thereto by a nipple 52 screwed on the front end of the button and loosely received in the recess 47. A safety wire 53 extends through the radial passages 48 and through an aligned opening in the nipple 52 so as to lock the diaphragm positively in its pre-stressed position. One end of the safety wire is bent around the side of the nose cap, as shown at 53a, while the other end is provided with a loop 53b bent around the opposite side of the nose cap and lying flat against the front face of the cap, so that the wire is held securely in the cap.

A ring 55 is slidably mounted on the outer cylindrical surface of the body 11 and is engageable at its rear end with inclined cam surfaces 56 on the bell-crank levers. The front end of 30 the ring is engageable with similar cam surfaces 51 on the levers.

In the use of the new fuze, the casing 10 is secured in a suitable recess in the nose portion of the projectile casing, and for this purpose I 35 provide the nose cap 45 with an externally threaded course 59 which may be screwed into the recess. A sealing gasket 60 may be inserted between a flange 61 on the nose cap and the rim of the fuze opening to seal the interior of the 40 projectile. Preferably, the interior of the casing 10 is vented to the inside of the projectile through a port 62 in the casing wall.

In the normal condition of the fuze, the lever arms 37 and 37a are held in their innermost positions by the diaphragm through the button 52, so that the gate 27 and striker 22 are locked in their safe positions. Also, the diaphragm is locked in its pre-stressed position by the wire 53 so that the fuze may be handled safely without danger of accidental operation of the diaphragm. Before the projectile is directed to the target, the wire 53 is withdrawn from the passages 48 and the nipple 52 so as to release the diaphragm, the loop 53b serving as a handle for this purpose. 55 As the wire is withdrawn, it cleans the passages 48 and thereby insures proper flow of water into the chamber 46 as the projectile moves through the water.

When the projectile is fired through the air, the resulting force of set-back causes the ring 55 to move rearwardly on the body 11 and engage the cam surfaces 56 on the bell-crank levers, so that the ring supplements the holding action of the diaphragm 44 in preventing accidental outward movement of the lever arms 37 and 37a due, for example, to spinning of the projectile. When the nose of the bomb strikes the water, the resulting force of reverse set-back causes the ring 55 to move forwardly against the cam surfaces 57 on the levers where it also prevents accidental outward movement of the lever arms. In either position of the ring, the lever arms 37 and 37a are prevented from moving outwardly except by a considerable force on the levers sufficient to slide the ring to an intermediate position.

by the cam action of the surfaces 56 or 57. It will be apparent that when the fuze strikes the water, the shoulders 39 and 39a on the lever arms prevent the striker 22 from moving off the ball bearings 19 which support the striker. As the projectile moves through the water, the radial passages 48 permit entrance of water into the chamber 43 adjacent the diaphragm, the water pressure in the chamber increasing as the projectile moves to a greater depth. When the pressure on the front face of the diaphragm is sufficient to overcome its pre-stressing and to slide the ring 55 rearwardly through action of the cam surfaces 57, the diaphragm snaps to its opposite position against the concave face of the nose disc and moves the lever arms 51 and 51a rearwardly on the pivots 42. As a result, the lever arms 37 and 37a move outwardly to the dotted line positions shown in Fig. 1 and release the striker head 22 and the gate 27. The gate is then moved to its armed position by the springs 29 so as to aline the semi-cap in opening 28 with the firing pin 14. Preferably, the gate is locked in its armed position by a detent 62a mounted in the flange 11a and urged into one of the gate recesses 36 by a compression spring 63.

Upon movement of the lever shoulders 39 and 39a away from the striker flange 24, the striker remains on the ball bearings 19 as long as the fuze moves through the water without striking an object. However, when the fuze strikes an under-water object head-on, the resulting impact causes the striker head to move forwardly in the casing due to the inertia of the head. Accordingly, the ball bearings 19 are forced inwardly against the cam 20 by the rear edge of the striker recess 23, with the result that the firing pin is retracted further against the action of the operating spring 15, and the bearings move into the annular recess 21. The striker head is thus released from the bearings and falls against the nose disc 40, permitting the bearings to move outwardly through boss 18 by the action of the cam 20 and spring 15. The firing pin, therefore, is released and moved by the spring 15 with a snap action against the semi-cap (not shown) in the gate 27, and the semi-cap fires through the opening 33 so as to detonate the charge in booster 34 and explode the projectile. In the event that the projectile should strike the under-water object with a glancing blow, the resulting sidewise impact causes the striker head 22 to pivot on the end of the outer boss 17, which is rounded to permit such action. As the striker pivots, the ball bearing (or bearings) opposite the pivoting point is displaced inwardly, against the spring action of cam 20, by the rear edge of the striker recess 23, and the latter rides over the displaced bearing (or bearings) whereby the striker is released and the firing pin is actuated. The sensitivity of the striker head assembly is governed by the weight of the head, the strength of the firing spring 15, the height of the rear wall of striker recess 23 which moves over the bearings, and the smoothness of the working surfaces. The sensitivity to sidewise impact is also dependent upon the length of the striker head, which determines the moment arm of the force tending to pivot the head on the end of boss 17.

The new fuze is safe against accidental operation due to dropping or jolting, because the bell-crank levers hold the striker and the safety gate positively in place until the levers have been forced outwardly by hydrostatic pressure on the diaphragm. The symmetry of the levers is such

that the effect thereon of sidewise blows is neutralized for the reason that when a blow tends to move one of the levers outwardly it also tends to move the other lever inwardly, the interlocking button 50, however, preventing independent movement of the levers. Similarly, the effects of shaking the fuze are cancelled out by the opposing action of the levers.

When the projectile strikes the water surface, it is immediately decelerated and a dynamic water pressure is built up on the nose for a fraction of a second, during which time the diaphragm tends to operate the levers and arm the fuze. If arming should occur while the deceleration is still sufficient to release the striker 22, the fuze would fire on or shortly after impact with the water, but such premature arming is prevented partly by the time lag required to operate the diaphragm and arming mechanism and partly by the action of the safety sleeve 55 in increasing the pressure required to operate the diaphragm. By properly proportioning the effective area of the diaphragm, the fuze may be made to arm at approximately any desired depth. While the speed of the projectile in the water has some effect on the arming depth, due to the resulting dynamic pressure on the diaphragm, the effect is relatively small due to the arrangement of the ports 48 in the side of the nose cap. Since the diaphragm is relatively heavy and in its collapsed position is completely supported by the nose disc 40, the fuze remains operative at substantial depths, at least to the extreme depths to which submarines can submerge.

When the fuze is subjected to a strong forward acceleration, as in firing the projectile from a gun, the lever arms 37 and 37a may tend to rotate about their pivots in such a direction as to permit arming, but premature movement of the levers is prevented by the restoring force of the diaphragm and by the action of the safety ring 55 on cam surfaces 57. Since the holding force of the ring against the cams 57 is proportional to the acceleration, no amount of acceleration can arm the fuze.

The fuze shown in Fig. 3 comprises a cylindrical casing 64 containing a hollow body 65 which has an axial passage for receiving a firing pin 66. At its rear end, the body 65 has an external flange 65a which fits closely in the casing so as to support the main part of the body in concentric relation to the casing wall. A safety gate 67 is slidable in a transverse slot in the rear face of the body 65, the gate being similar to the gate 27 shown in Figs. 1 and 2 and having a semi-cap (not shown) adapted to be engaged by the firing pin. When the semi-cap is alined with the firing pin and the latter is operated, the cap fires through an opening 68a in a disc 68 mounted on the rear face of the flange 65a over the safety gate, the blast being directed into a booster charge in a container 69. The booster container is threaded into the rear end of the casing against the disc 68 to hold the parts in the casing.

Normally, the safety gate 67 is locked in a safe position wherein the semi-cap is offset laterally from the firing pin and the opening 68a so that accidental operation of the pin cannot fire the semi-cap and detonate the booster charge. The gate is locked in its safe position by a wire 70 extending transversely through the gate, the flange 65a and the casing, the wire having a loop 70a serving as a handle for withdrawing the wire from the casing to release the gate when the

fuze is to be operated. The gate is also locked in its safe position by the arms 71 of a pair of opposed bell-crank levers, the free ends of the arms normally extending into slots 67a in the opposite sides of the gate. The free end portions of the arms 71 lie in diametrically opposed slots 72 in the flange 65a, whereby the arms are movable radially in the casing and are guided in their movements.

The bell-crank levers 71 are pivoted on pins 74 mounted in a split disc 75 in the nose of the casing. The rear face of the disc 75 engages and supports the front end of the hollow body 65 and has a hollow boss 75a telescoping in a similar boss on the hollow body. Within the body 65 and the split disc 75 is a compression spring 76 coiled around the firing pin and seated at its rear end against a shoulder 66a on the pin. The firing pin is provided with a similar shoulder 66b to the rear of the shoulder 66a, and between the shoulders is a set of ball bearings 77 mounted in openings in the side wall of the hollow body 65. The bearings 77 are normally held in the annular space between the shoulders 66a and 66b by a striker ring 78 having a beveled cam surface 78a engaging the bearings, the ring 78 extending around the hollow body 65 and being fitted closely in the fuze casing. A sleeve 79 extends around the hollow body 65 between its flange 65a and the striker ring 78, and the ends of the sleeve are seated on concave cam surfaces 80 and 80a on the ring and flange, respectively. The ring 78 is locked in position on the bearings 77 by shoulders 71a on the bell-crank levers.

A nose cap 82 is secured on the front end of the casing 64 and has an externally threaded course 82a which may be screwed into a suitable receptacle in the projectile casing (not shown). The cap 82 also has an internal flange 82b for retaining the nose disc 75 in the casing. Within the nose cap 82 is a flexible, pre-stressed diaphragm 83 which is clamped around its periphery by a plug 84 threaded in the nose cap and having a hollow boss 84a on its front end. The plug 84 has a recess defining a chamber 85 in front of the diaphragm, and the chamber communicates through the hollow boss 84a with radial passages 84b extending to the outside of the casing. A safety wire 86 extends through the passages 84b and through a pin 87 connected to the central portion of the diaphragm, so that the latter is normally locked in its pre-stressed position, the wire having a loop 86a at one end for use in removing the wire to release the diaphragm. The arms 88 of the bell-crank levers extend inwardly adjacent the diaphragm and engage the front end of the firing spring 76.

In operation, the safety wires 10 and 86 are removed prior to firing a projectile containing the fuze. When the projectile is fired, it travels through an air trajectory and strikes the water nose-first, and during this time the safety gate 67 is locked in its safe position by the free ends of lever 71, and the striker ring 78 is locked against movement by the lever shoulders 71a. The levers are held in their locking positions by the forward thrust of spring 76 on the lever arms 88, whereby the safety gate and the striker ring remain locked in their safe positions after impact of the projectile with the water surface. As the projectile moves through the water, the passages 84b permit entrance of water into the chamber 85, the water pressure in the chamber increasing with the depth to which the projectile moves. When the water pressure on the diaphragm is sufficient to

overcome its pre-stressing, the diaphragm is snapped to a position of opposite curvature against the concave face of nose disc 75 and the inner ends of the lever arms 88. As a result, the arms 71 are moved outwardly on their pivots 74 against the action of spring 76, thereby releasing the safety gate and striker ring. The gate is then moved to its armed position in which the semi-cap (not shown) is aligned with the firing pin and the opening 68a.

On release of the striker ring 78, the latter continues to be held by the ball bearings 77 against sleeve 79, but when the projectile strikes an underwater target head-on, the striker ring 78 moves forwardly under the force of reverse setback and displaces the bearings 77 inwardly against shoulder 66a and spring 76. The striker is thus released from the bearings and moves against the rear face of disc 75. The bearings 77 are thereupon forced outwardly by spring 76 acting through shoulder 66a, so as to release the firing pin which is then actuated by the spring to fire the cap in gate 67 and explode the booster charge. In the event that the projectile strikes the target a glancing blow, the resulting sidewise impact causes sleeve 79 to move laterally between the cam surfaces 80 and 80a, the cam surfaces acting to translate such lateral movement of the sleeve into a forward thrust on the striker ring 78. The ring is thus forced over the bearings 77 to release the firing pin, as previously described.

The fuze shown in Fig. 4 is similar to that illustrated in Fig. 3 except for the arrangement of the firing pin and the striker ring. As shown in Fig. 4, the fuze includes a firing pin 90 having a single shoulder 91 normally engaged by the ball bearings 77 which lock the pin in a retracted position against the compression spring 76. The bearings 77 are normally held in their locking positions by a ring 92 having a beveled cam surface 92a engaging the bearings, the ring 92 being normally locked against the bearings by shoulders 93 on the lever arms 71. When the lever arms are moved outwardly by the water pressure on diaphragm 83, the safety gate 67 is first released so that it moves to its armed position before the shoulders 93 release ring 92. Accordingly, when the arms 71 complete their outward movement and release ring 92, the latter is urged rearwardly by the action of spring 76 on the bearings 77, whereby the bearings are forced outwardly and the firing pin is snapped against the semi-cap in gate 67.

A modification of the fuze shown in Fig. 4 is illustrated in Fig. 5. As there shown, the fuze casing 64c has a nose cap 82c containing a pre-stressed diaphragm 83c, the central portion of which is reenforced by a disc 95. The diaphragm is clamped around its periphery by a plug 84c threaded in the nose cap, the plug being recessed to provide a chamber 85c in front of the diaphragm. Threaded in the plug 84c are frangible horns 96 projecting forwardly from the fuze. The horns may be made of a plastic material, or the like, and their inner end portions are formed with axial passages 97 communicating with chamber 85c. In operation, when one of the horns 96 strikes an under-water target, the horn is broken by the impact. As a result, water enters the chamber 85c through the passage 97 in the broken horn, the pressure of the water forcing the diaphragm to a position of opposite curvature against the lever arms 87 (Fig. 4). The levers are thus actuated to release the operating elements in casing 64c.

It will be observed that all of the forms of the new fuze, as illustrated, are armed hydrostatically, and the forms shown in Figs. 4 and 5 are fired under hydrostatic control while the other forms are impact-fired. It is to be understood that the invention is not limited to the constructions illustrated but is susceptible of various modifications within its scope. For example, instead of arranging the diaphragm for operation by water pressure, it may be made to operate by the gas pressure from a rocket motor adapted to propel the projectile, as by mounting the fuze between the projectile and the rocket motor so that the diaphragm chamber may communicate with the pressure chamber in the motor, and in the preceding description and the appended claims, the term "hydrostatic" is intended to include within its range of equivalents any gaseous medium.

I claim:

1. A fuze comprising a firing device, safety means normally maintaining the firing device ineffective and movable to an operating position to render said device effective, a pair of opposed bell-crank levers each having one arm locking the safety means in its normal position against movement, a diaphragm adjacent the other arm of each lever and operable hydrostatically to move the levers for releasing the safety means, and a member on the central portion of the diaphragm engaging the free end portions of said last arms and confining said free end portions between the diaphragm and said member, whereby the levers are interlocked with the diaphragm.

2. In a fuze having a firing pin, the combination of a hollow body in which the pin is slidable, a hollow boss on the body, a cam on the pin disposed in the boss, a striker head, a hollow boss on the head surrounding said first boss and having a recess in its inner wall, ball bearings mounted in openings in the side wall of said first boss and engaged in said recess and with the cam, said bearings being held by the head against the cam to lock the pin against operation and being held by the cam in said recess to support the head on the body, and biasing means for operating the pin and urging the cam against the bearings, the head being pivotable on the body upon sidewise impact of the fuze to force at least one of the bearings inwardly against the spring action on the cam and thereby release the head, whereby the bearings are movable outwardly by the cam to release the pin.

3. A hydrostatically armed, impact fired fuze comprising a casing, a body in the casing having a longitudinal passage extending lengthwise of the casing, a firing pin slidable in the passage, biasing means for urging the pin slidably along

the passage to detonate the fuze, bearing means mounted in the body, a striker head normally holding the bearing means against part of the pin for locking the pin in a retracted position against the biasing means, the biasing means acting through the pin to hold the bearing means in position to support the head, a pair of opposed bell-crank levers in the casing on opposite sides of said body and each having one arm locking the head against movement on the bearing means, and a diaphragm in the casing adjacent the other arm of each lever and operable hydrostatically to move the levers and release the head, whereby the head becomes movable upon subsequent impact of the fuze to displace the bearing means and thereby release the pin.

4. A hydrostatically armed, impact fired fuze comprising a casing, a hollow body in the casing, a firing pin slidable in the body, a striker head in the casing normally locking the firing pin in a retracted position, a pair of opposed bell-crank levers in the casing on opposite sides of said body and each having one arm locking the head against movement, a diaphragm in the casing adjacent the other arm of each lever and operable hydrostatically to move the levers and release the head, the head being movable upon operation of the diaphragm and subsequent impact of the fuze to release the firing pin, and a ring slidably mounted on the body and normally engaging the levers to secure the same against movement independently of the diaphragm, the ring being movable by the diaphragm through the levers to release the levers.
